United States Patent Office

Des. 178,933
Patented Oct. 9, 1956

178,933

COMBINED RADIO, RECORD PLAYER, TELE- VISION AND SPEAKER ENCLOSURE

Alexander Rauchman, New York, N. Y.

Application February 27, 1956, Serial No. 40,336

Term of patent 7 years

(Cl. D56—4)

Des. 178,933

PAGE 2

FIG 2

Des. 178,933

Fig 3

Fig. 5

Fig. 4

Fig. 1 is a front elevational view of a combined radio, record player, television and speaker enclosure, showing my new design;

Fig. 2 is a side elevational view thereof;

Fig. 3 is a top plan thereof;

Fig. 4 is another front elevational view with the compartment doors in open position; and

Fig. 5 is a side elevational view of that shown in Fig. 4.

The rear of the cabinet is a plain and conventional configuration.

I claim:

The ornamental design for a combined radio, record player, television and speaker enclosure, as shown and described.
